ATTORNEYS

UNITED STATES PATENT OFFICE.

BERTON I. RIKE, OF DAYTON, OHIO, ASSIGNOR TO THE RIKE FOLDING BOX COMPANY, OF DAYTON, OHIO, A CORPORATION OF OHIO.

CLOTHES BAG.

Application filed June 2, 1921. Serial No. 474,341.

To all whom it may concern:

Be it known that I, BERTON I. RIKE, a citizen of the United States, residing at Dayton, in the county of Montgomery and State of Ohio, have invented certain new and useful Improvements in Clothes Bags, of which the following is a specification, reference being had therein to the accompanying drawing.

10 My invention relates to receptacles and in particular to paper or fiber receptacles for containing clothes.

It is the object of my invention to provide a clothes bag that may be completely sealed 15 to prevent the entrance of moth or dirt to attack clothes contained within the bag. It is my object to provide a bag in which the clothes upon a clothes hanger may be inserted or removed without disturbing the 20 bag or disturbing its being sealed or unsealed.

It is a further object to provide a bag which when sealed may be locked in sealed 25 position. It is my object to provide a bag which will be susceptible of being sealed doubly and then locked in sealed position or unlocked at the will of the user.

It is my object to provide a bag which may be folded when not in use in a small 30 compass so that it may be put in a traveling case or otherwise transported conveniently and economically.

Referring to the drawings:

Fig. 1 is a perspective of the top of the 35 bag with a hanger in place, the bag being unsealed;

Fig. 2 is a plan view of the bag showing the lines along which it may be folded;

Fig. 3 is an interior view looking out- 40 wardly and the specific method of inserting the hanger in the bag;

Fig. 4 is a similar view from the exterior of the bag;

Fig. 5 is a section on the line 5—5 of Fig- 45 ure 2;

Fig. 6 is a section on the line 5—5 of Fig- ure 2 when the bag is sealed.

Fig. 7 is a perspective of the top of the 50 bag with a modified form of sealing mem- bers.

Fig. 8 is a horizontal section of one end of the bag when folded and sealed.

Referring in detail to the drawings, 1 is

a bag sealed at the bottom 2 and on the sides 3—3. It is open at the mouth 4.

55

About the mouth 4 are certain reinforcing and folding strips arranged as follows. On the front is a reinforcing strip 6 and on the rear a corresponding strip 21 which may be integral with one another joined at the ends 60 or separate strips. That is immaterial.

Joined to 6 and hinged thereto at 8 is a folding and reinforcing strip 5 that is integrally connected at the ends thereof to a rear folding and reinforcing strip 22. 65 Hinged to 22 at 10 is a folding strip 9. 21 and 22 are hinged together along the line 23. Just above the line 23 is an aperture 11 that is connected to a slot 12 which severs 22 and 9 so that the shaft 13 of a hanger 70 may be inserted therein. To the hanger at the bottom of the shaft is a transverse member 15 for supporting the clothes and at the outer end thereof a hook 14.

Referring to Figure 2, there will be seen 75 creases 17—17 and creases 18—18 in the forward and rear reinforcing and folding members respectively. These creases are inserted for the purpose of folding the bag when empty along the dotted lines 19 so that the bag will take the shape of a square or rectangle, such as 20 for convenient insertion into a traveling bag.

Referring to Figures 7 and 8, there will be 80 seen attached to 9 a flap 24 and a metal reinforcing member 25. The flaps 22 and 5 are held together by the overlapping flaps 26 and the reinforcing members 21 and 6 are held together by the flaps 27 at their ends.

The bag when folded is folded as de- 85 scribed above, with the addition of the end flaps 24 with their metal reinforcing mem- bers being turned back upon the folded por- tions to lock the ends.

90

95

Method of operation.

The clothes are hung upon the hanger and lowered into the open bag. The shaft 13 is inserted through the slot 12 until it rests 100 within the aperture 11. The mouth of the bag is then drawn together and the rear sealing member 9 turned over and upon the for- ward reinforcing member 5. Then 5 and 9 as a unit, together with 22, fold over upon 105 6. See in particular sections shown in Fig-

ures 5 and 6. The metal clamping members 7 that are fastened between the bag proper and 6 are turned over upon the folded sections and clamped thereon to retain the 5 folded sections in position.

It will be thus apparent that there is a complete sealing of the open end of the bag sealing the clothes therein.

Having thus fully described my invention, what I claim as new and desire to secure by Letters Patent, is:-

1. In a clothes bag, a bag body sealed at the bottom and sides with an open mouth, means for insertion through a portion of 15 the edge of the mouth of a hanger, reinforcing means adjacent the bag mouth partially cut away at spaced intervals to permit of folding, means to seal the end of said bag with the hanger therein by folding over 20 upon itself said reinforcing means, and means to permit of the bag when empty to be folded upon itself into a package of smaller area than its greatest dimensions along the line of the cut away portions in 25 the reinforcing means.

2. In a clothes bag comprising a receptacle with a sealed bottom and sides and an open mouth, a first reinforcing and folding band attached to one face of the receptacle 30 at its mouth and projecting beyond the receptacle, a second reinforcing and folding

band attached to the other face of the receptacle and projecting beyond the said first band, a tab formed integrally with said second band to close the slit at the ends of the bands, stiffened reinforcing tabs formed at the ends of the projecting portion of said second band, and metal clamping members fastened at intervals on said first band, whereby said projecting portion of said second band may be bent over said first band and secured in such bent position by means of said stiffened tabs, and thereupon such folded portion refolded and secured by said clamping member.

3. In a clothes bag comprising a receptacle with sealed bottom and sides and an open mouth, a reinforcing and folding band attached to one face of the receptacle at its mouth and projecting beyond the receptacle, and having the portion thereof at one face of the receptacle projecting beyond the portion at the other face of the receptacle, said projecting portion being adapted to fold over the portion of the band at the other face 55 to close the mouth slit, and the folded portion thus formed being adapted to be refolded to close the corner openings.

In testimony whereof, I affix my signature.

BERTON I. RIKE.
